FLAGSTAFF

Alexis de Sakhnoffsky, Grand Rapids, Mich., assignor
to Attwood Corporation, a corporation of Michigan

Filed Apr. 13, 1960, Ser. No. 60,173

Term of patent 14 years

(Cl. D71—1)

FIG. 1 is a front elevation of a flagstaff, showing the design of my invention.

FIG. 2 is a side elevation of the flagstaff shown in FIG. 1.

FIG. 3 is a top plan view thereof;

FIG. 4 is a plan view of the bottom of the flagstaff shown in FIGS. 1 and 2.

FIG. 5 is a sectional view on the line V—V of FIG. 2 in the direction of the arrows;

FIG. 6 is a sectional view on the line VI—VI of FIG. 2 in the direction of the arrows.

The conventional base support element disclosed in broken lines in FIGS. 1, 2 and 4 is broken away in FIGS. 1 and 2 for convenience of illustration.

I claim:

The ornamental design for a flagstaff, substantially as shown and described.
